[57] CLAIM

The ornamental design for a toy garage, as shown and
described.

DESCRIPTION

FIG. 1 is a front perspective view of a toy garage showing
the key of the toy garage exploded from the garage
unit and embodying my new design.

FIG. 2 is a side elevational view thereof; the opposite
side being a mirror image.

FIG. 3 is a front elevational view thereof.

FIG. 4 is a top plan view thereof.

FIG. 5 is a bottom plan view thereof.

FIG. 6 is a rear elevational view thereof.

FIG. 1

FIG. 2

FIG. 3

FIG. 4
